UNITED STATES PATENT OFFICE.

LOUIS GREENBERG, OF INDIANAPOLIS, INDIANA.

MECHANICAL MOVEMENT.

1,317,365.

Specification of Letters Patent. Patented Sept. 30, 1919.

Application filed September 15, 1917, Serial No. 191,518. Renewed January 29, 1919. Serial No. 273,880.

To all whom it may concern:

Be it known that I, LOUIS GREENBERG, a citizen of the United States, residing at Indianapolis, in the county of Marion and State of Indiana, have invented new and useful Improvements in Mechanical Movements, of which the following is a specification.

This invention relates to a device embracing a novel mechanical movement.

Among the objects of my invention is to provide a mechanical movement wherein a member, such as a search light or the like, may be revolved bodily about a vertical axis and simultaneously be tilted up and down in a vertical plane on a horizontal axis, or such member may be held in one or more fixed inclinations to and at the same time be turned bodily about a vertical axis, such movements being effected by positive mechanical means. It is a further object of my invention to provide a mechanical movement wherein said member, if a search light, will be made to project a ray of light at least once on every point within the compass of its path of movement, so that there is not a point within the compass of its movement that will not be illuminated by said light at least once during the operation of my device.

The invention consists further in the matters hereinafter described and more particularly pointed out in the appended claims.

In the accompanying drawings—

Figure 1 is a front elevational view of a search light equipped with a device embodying a mechanical movement constructed in accordance with my invention;

Fig. 2 is a vertical sectional view taken on the indirect line 2—2 of Fig. 1; and

Fig. 3 is an enlarged horizontal sectional view showing a detail of construction and taken on line 3—3 of Fig. 2.

In the drawings I have shown a device embodying features of my invention and used in connection with a search light, but it is of course to be understood that my device may be put to other uses and that I have shown it applied to a search light merely to illustrate its structural features and the manner in which it operates. As shown, said device comprises a base or supporting member 10, preferably made in the form of a hollow housing or casing, cylindrical in shape and having a bottom wall 11 and upright side or marginal walls 12. Located

at the top of said casing and suitably secured thereto is an annular member 13, preferably in the form of a spider having radial arms or webs 14 horizontally disposed and extending between an outer rim in the form of an angle member 15 and a centrally arranged bearing member 16. Extending vertically through said member 16 are two hollow shafts or spindles 17, 18, one journaled for rotation within the other and extending vertically above and below said member 16, as shown in Fig. 2. The outer shaft 17 is provided with a downwardly facing annular shoulder 19 adapted to bear on a washer 20 interposed between said shoulder and the member 16, for allowing the outer shaft to rest on said spider. The inner shaft 18 extends upward beyond the upper end of the outer shaft, and is provided with a downwardly facing annular shoulder 21 bearing on a washer 22 interposed between the said shoulder and the upper end of the outer shaft 17 for allowing the inner shaft to rest on the outer one, as shown in said Fig. 2. Said washers may be provided with anti-friction bearing balls if desired. The upper end of said inner shaft is bifurcated or forked to receive a downwardly extending lug 23 provided centrally on a cross-arm 24. Said lug 23 is pivoted in said fork by a horizontally arranged pivot pin 25, which may be in the form of a screw-threaded bolt and nut, as shown in Fig. 1. The search light 26 is mounted on said cross-arm 24, above the same, and is connected therewith by a yoke member 27, between the arms of which the casing of the search light is mounted, so as to be swung about a substantially horizontal axis. A clamp screw 28 secures the yoke 27 to the cross-arm 24, as shown in Fig. 2. Connected to that portion of the outer shaft 17 between the upper end of the inner shaft and the member 16, is an annular member 29, arranged concentric to said outer and inner shafts and having its upper edge in the shape of a wave like track 30, upon which travel rollers 31, 31, carried by the cross-arm 24.

For rotating said inner and outer shafts 17, 18, I provide the following construction. As shown in Fig. 2, the lower end of the inner shaft 18 extends downward below the corresponding end of the outer shaft 17 and has secured thereto a gear wheel 32 horizontally disposed, as shown, while to the lower end of the outer shaft 17 is secured

a gear wheel 33, also horizontally disposed. Said gear wheels may or may not have the same diameter and may be provided with any number of teeth desired. Located 5 within the casing 10 is a prime mover, preferably in the form of an electric motor 34, suitably secured to and supported by the bottom wall 11. The armature shaft 35 of said motor is horizontally arranged and has 10 secured thereto a pinion 36 having worm teeth meshing with two worm wheels 37, 38, both horizontally disposed and on opposite sides of said pinion 36. Said worm wheels are secured to vertical shafts 39, 40 supported and journaled in the gear case 41 inclosing the worm wheels and meshing pinion, as shown. The shaft 39 is provided at its upper end with a gear pinion 42, which meshes with the gear wheel 32 on the inner 15 shaft 18, while the shaft 40 is provided at its upper end with a gear pinion 43, which meshes with the gear wheel 33 on the outer shaft 17. Between each gear pinion 42, 43 and its associated shaft 39, 40 is a slideable 20 clutch member 44, 45 operated by suitable shifting levers 46, 47 fulcrumed intermediate their ends on the side walls of the casing 10 and having their handle portions extending outward therefrom through suitable vertical slots 48. The gear case 41 is 25 supported within the outer casing 10 and above the bottom wall thereof on suitable supporting members 49.

The operation of the device described and 30 shown is as follows: When the motor 34 is set in motion by supplying current thereto from a suitable source, its armature shaft 35 is rotated and through the worm 36 serves to rotate the worm wheels 37 and 38 in opposite directions. Said worm wheels rotate 35 the shafts 39, 40 in opposite directions, and the latter, through the gear pinions 42, 43, transmit motion through the gear wheels 32, 33 to the inner and outer shafts 18, 17, respectively, when both clutch members 44, 45 are engaged with said gear pinions. Under such conditions, the inner shaft 18 is 40 rotated in one direction and carries therewith the search light 26 and cross-arm 24, while the outer shaft 17 is rotated in the opposite direction and carries therewith the wave-like track member 29. It follows, 45 therefore, that the search light 26 is rotated bodily about a vertical axis and at the same time tilted up and down in a vertical 50 plane on the horizontal pivot pin 25, as the rollers 31 on the cross-arm 24 travel over the now revolving wave-like track 30. Manifestly, under such conditions, the search 55 light will project a beam of light constantly up and down in a vertical plane while it is revolved bodily in a substantially horizontal plane. As shown in the drawings, the vertical shafts 39, 40 have the same diameter, 60 while the same is true of the gear pinions 65

42, 43, but the worm wheels 37, 38 have different diameters, as shown. With respect to the gear wheels 32, 33, however, one is larger in diameter than the other and it follows that, when both clutch members 44, 45 are in engagement with the gear pinions 42, 43, said shafts 17, 18 are rotated at different rates of speed, although in opposite directions. The result is that the wave-like track member 29 is rotated at a different rate of speed than the search light 26 and its cross-arm 24. Therefore, the search light, in the operation of my device under the conditions stated, will project a beam of light on every point within the compass of its path of movement, but no one point will be illuminated twice in succession. This may be more clearly understood by noting the following: As shown in the drawings, the wave-like track 30 has a plurality of crowns or high parts and a like number of depressions or low parts, and with a crown diametrically opposite a depression. Thus the search light 26 will be tilted upward to the fullest extent a plurality of times and be tilted downward to the fullest extent a plurality of times as the track member 29 revolves, with a tilt of lesser degree between such parts. As the track member 29 is revolved at a different rate of speed than the search light and in the opposite direction, it follows that when the search light reaches a predetermined point in its bodily rotation in a horizontal plane, it may be tilted upward to the fullest extent by one of the crowns or high parts of the wave-like track, but when the search light reaches the same point in the following revolution it will not be tilted to the same extent as in the preceding revolution, but will be either tilted downward to the fullest extent by a depression or low part on said wave-like track 30, or be tilted to a less extent by a portion of said wave-like track intermediate such high and low parts. The result is that, when both of the shafts 17, 18 are rotated at the same time, but in opposite directions and at different rates of speed, the search light will be caused to throw a beam of light on every point in the horizon at some time during its operation, but will not illuminate one fixed point twice in succession. A second movement may be accomplished by shifting one of the clutch members out of engagement with its gear pinion. For example suppose that the clutch member 44 is shifted by the lever 46 out of engagement with the gear pinion 42, so that no motion will be imparted to the gear wheel 32. Under such conditions, the outer shaft 17 will be rotated by the motor 34, and as the search light 26 is rather heavy in weight, the same will probably be carried around with the revolving member 29 and will be maintained at a fixed indication, either up or down, depend-

ing on where the rollers 31 bear on the track 30. Thus, the inclination of the search light may be fixed beforehand, and then be revolved bodily about a vertical axis at such 5 fixed inclination.

If a rather light apparatus, such as an electric fan or light display figure, were mounted on the cross-arm 24, the inner shaft 18, under such conditions, might be maintained more or less stationary by the frictional lock between the gear pinion 42 and the gear wheel 32, with the result that such light device would be tilted up and down in a fixed vertical plane on the horizontal pivot 10 pin 25, due to the fact that the wave-like track member 29 would be rotated by the outer shaft 17 and that such light device would not be carried around with said member 29 during the rotation thereof. A third 15 motion may be obtained by throwing in the clutch member 44 and throwing out the clutch member 45, whereupon the motor would not transmit power to the outer shaft 17, but would transmit power to the inner shaft 18, and thus serve to rotate the search light bodily about a vertical axis with the inner shaft. The search light being heavy in weight would probably carry therewith the member 29, and the degree of inclination 20 of the search light would be fixed, depending upon the position of the rollers 31 on the wave-like track 30. If a rather light device should be mounted on the cross-arm 24, the same under such conditions would in all probability be tilted up and down as the rollers 31 travel over the wave-like track member 29, which in such case would be held against rotation by the lock between the gear pinion 43 and the gear wheel 33. 25 If both clutch members 44, 45 are thrown out, it of course follows that the motor 34 will not impart motion to the inner and outer shafts 18 and 17, and under such conditions the search light 26 may be manually tilted up and down between the fork 27 and may also be manually turned or revolved 30 about a vertical axis and thus be used in the same manner as an ordinary search light.

For supplying electric current to the 35 source of light in the search light casing 26, I provide two insulated conductors or wires 50, 50 extending vertically through the inner shaft 18, which is made hollow for that purpose. As shown in Fig. 1, said wires 55 are carried upward through the arms of the yoke 27 and into the search light casing through the trunnions 51, which pivot said casing between said arms in the usual manner. Extending downward from the gear 60 wheel 32 and secured thereto is an annular flange 52. Secured to the outside of said flange are two vertically spaced contact rings 53, 53 insulated from each other and from said flange by an annular insulating 65 ring 54, as shown in Figs. 2 and 3. Bearing

against the outer face of each contact ring is a resilient contact member or brush 55, 55 to which is connected a conductor wire 56, the latter leading to a source of electric supply. By the construction described, an 70 electric current is supplied to the source of light in the search light casing 26 during the rotation of the latter about a vertical axis and during its tilting movements up and down in a vertical plane on the horizontal 75 pivot pin 25 and the other movements that may be imparted to said search light by my device. Furthermore, the construction described prevents the conductor wires 50, 50 from being twisted during the rotation 80 of the search light and in its movements up and down in a vertical plane.

When using a heavy search light, as shown, and to enable my device to be so operated as to cause the search light to be 85 tilted up and down in a fixed vertical plane and not be carried around with the wave-like track member 29 during its rotation when the inner shaft 18 is disconnected from the motor 34, I provide a stop member 90 57, which, as shown in Fig. 2, is in the form of a set screw threaded through the bearing member 16 and adapted to engage the portion of the inner shaft 18 extending therethrough. In the claims I have used 95 the expression "two members adapted to be rotated relatively to each other," and by such expression I mean that the cross-arm 24 and any apparatus that it supports constitutes one of such members, while the 100 member 29 constitutes the other of such members.

It will be particularly noted that by the construction described and shown, the rotation of the search light 26 about a vertical 105 axis is caused by positive mechanical means, whether the search light is rotated in a direction contrary to the direction of the track member 29 or not, thus being able to gain a positive and predetermined movement of the parts and thereby have complete control of such parts under all conditions, and also being able to project a beam of light on every point in the horizon.

A search light when equipped with my 115 device may be used for a number of different purposes. It may be used at night on patrol boats at sea for detecting the presence of hostile craft, both of the marine and air types, and operated without the constant 120 attendance of a man after once being set in operation. Then again, it may be used in commercial pursuits, as for advertising or displaying purposes. In such uses, it may be placed on the top of store building 125 or in another elevated position and serve as a means for attracting attention to such store. Moreover, it may be placed on the top of a tall building or tower in a town and serve when operated to attract the at- 130

tention of people in the surrounding territory to such town.

Although I have shown my device as used in connection with a search light, it is of course to be understood that said device may be used in connection with other apparatus, such as electric fans or display figures for advertising purposes and the like, and, while I have shown and described in 10 detail one preferred form of my device, yet it is to be of course understood that the details of construction and arrangement of parts shown may be variously changed and modified without departing from the spirit 15 and scope of my invention, and I do not wish to be limited to the exact details of construction and arrangement of parts illustrated, except as pointed out in the appended claims.

20 I claim as my invention:

1. A device of the character described, comprising two members adapted to be rotated relatively to each other, said members being provided with coacting means adapted 25 to effect the tilting of one of said members about an axis transverse to the axes of rotation of said members, and mechanical means for positively rotating each of said members.

30 2. A device of the character described, comprising two members adapted to be rotated relatively to each other about coinciding axes, said members being provided with coacting means adapted to effect the tilting 35 of one of said members about an axis transverse to the axes of rotation of said members, and mechanical means for positively rotating each of said members.

3. A device of the character described, 40 comprising two members adapted to be rotated relatively to each other, said members being provided with coacting means adapted to effect the tilting of one of said members about an axis transverse to the axes of rotation of said members, and mechanical means for positively rotating said members relatively to each other and in opposite directions.

4. A device of the character described, 45 comprising two members adapted to be rotated relatively to each other, said members being provided with coacting means adapted to effect the tilting of one of said members about an axis transverse to the axes of rotation of said members, and mechanical means for positively rotating said members relatively to each other at different rates of speed and in opposite directions.

5. A device of the character described, 50 comprising two members adapted to be rotated relatively to each other, one of said members being provided with an annular wave-like track and the other having engagement with said track so as to be tilted 55 about an axis transverse to the axes of rota-

tion of said members, and mechanical means for positively rotating each of said members.

6. A device of the character described, 70 comprising two members adapted to be rotated relatively to each other, one of said members being provided with an annular wave-like track and the other having engagement with said track so as to be tilted about an axis transverse to the axes of rotation of said members, and mechanical means for positively rotating each of said members and in opposite directions.

7. A device of the character described, 75 comprising a tiltably mounted member and an annular member, both being adapted to be rotated relatively to each other, one of said members being provided with a wave-like track and the other of said members being provided with rollers bearing on said track, and mechanical means for imparting a positive rotation to each of said members.

8. A device of the character described, 80 comprising two concentric shafts, one journaled within the other and adapted to be rotated relatively to each other, a member tiltably mounted on one of said shafts, an annular member on the other of said shafts and provided with a wave-like track, said tiltably mounted member having rollers 95 bearing on said track, and mechanical means for imparting a positive rotation to each of said shafts.

9. A device of the character described, 100 comprising two concentric shafts, one journaled within the other and adapted to be rotated relatively to each other, a member tiltably mounted on one of said shafts, an annular member on the other of said shafts and provided with a wave-like track, said tiltably mounted member having rollers bearing on said track, each of said shafts being provided with a gear wheel, and means for driving each of said gear wheels.

10. A device of the character described, 110 comprising two concentric shafts journaled one within the other and adapted to be rotated relatively to each other, a member tiltably mounted on one of said shafts, an annular member on the other of said shafts 115 and provided with a wave-like track, said tiltably mounted member being provided with rollers bearing on said track, each shaft being provided with a gear wheel, the gear wheel on one of said shafts having a greater diameter than the gear wheel on the other of said shafts, and means for driving said gear wheels.

11. A device of the character described, 125 comprising two concentric shafts journaled one within the other and adapted for rotation relatively to each other, a member tiltably mounted on one of said shafts, an annular member on the other of said shafts and provided with a wave-like track, said tiltably 130

5 mounted member having rollers bearing against said track, each of said shafts being provided with a gear wheel, a motor, and a train of gearing whereby said motor may drive said gear wheels.

12. A device of the character described, comprising two concentric shafts journaled one within the other and adapted for rotation relatively to each other, a member tiltably mounted on one of said shafts, an annular member on the other of said shafts and provided with a wave-like track, said tiltably mounted member having rollers bearing against said track, each of said shafts being provided with a gear wheel, a motor, and a train of gearing including clutches whereby said motor may drive said gear wheels.

13. A device of the character described, comprising two concentric shafts journaled within each other and adapted to be rotated relatively to each other, a member tiltably mounted on one of said shafts, an annular member on the other of said shafts and provided with a wave-like track, said tiltably mounted member having rollers bearing against said track, each of said shafts being provided with a gear wheel, a motor, a train of gearing connecting said motor with said gear wheels, a clutch interposed between each gear wheel and said motor, and levers for shifting said clutches.

14. A device of the character described, comprising two concentric shafts journaled within each other and adapted to be rotated relatively to each other, a member tiltably mounted on one of said shafts and an annular member on the other of said shafts and provided with a wave-like track, said tiltably mounted member having rollers bearing on said track, mechanical means for positively rotating each of said shafts, and means for locking one of said shafts against rotation.

15. A device of the character described, comprising a fixed member, two vertical shafts concentrically arranged and journaled for relative rotation in said fixed member, a member tiltably mounted on one of said shafts, an annular member on the other of 50 said shafts and provided with a wave-like

track, said tiltably mounted member having rollers bearing against said track, a gear wheel on each of said shafts, a gear pinion meshing with each of said gear wheels, shafts for said gear pinions, clutches for 55 connecting said gear pinions with said last named shafts, gear wheels on said last named shafts, and a motor for driving said last named gear wheels.

16. A device of the character described, 60 comprising a fixed member, two vertical shafts concentrically arranged and journaled for relative rotation in said fixed member, a member tiltably mounted on the upper end of one of said shafts, an annular member on 65 the upper end of the other of said shafts and provided with a wave-like track, said tiltably mounted member having rollers bearing on said track, a gear wheel horizontally disposed and secured to the lower 70 end of each of said shafts, a gear pinion meshing with each of said gear wheels, each gear pinion being mounted on a vertically arranged shaft, a clutch for connecting each gear pinion with the shaft upon which it is 75 mounted, each of said last named shafts being provided with a worm gear, a motor having a driving shaft extending between said worm gears, and a worm gear pinion on said motor shaft and meshing with each 80 of said worm wheels.

17. A device of the character described, comprising a tiltably mounted member and a rotatably mounted member located below said tiltably mounted member, said members being provided with coacting means adapted to effect the tilting of said tiltably mounted member upon the rotation of said rotatably mounted member, and mechanical means located below said tiltably mounted 90 member for rotating said rotatably mounted member.

In testimony that I claim the foregoing as my invention, I affix my signature in the presence of two witnesses, this 13th day of 95 September, A. D. 1917.

LOUIS GREENBERG.
